TOY UMBRELLA

Manfred Kirschbaum, Berlin-Lichterfelde, Germany

Application September 4, 1952, Serial No. 307,890

10 Claims. (Cl. 135—20)

This invention relates to a fancy goods articles consisting of kerchiefs, preferably handkerchiefs, combined to an umbrella in such a way, that they are usable for their original purpose after the dismantling of the umbrella. A novel feature of construction enables to expand and to contract the umbrella, thereby providing for an additional use as a toy, which makes the kerchiefs more attractive to buyers.

The toy umbrella according to the invention consists of a handle comprising at least one wound kerchief, an expandible and contractible support provided at one end of the handle and a cover comprising at least one kerchief, removably attached to the support. For the structural elements of the umbrella inexpensive materials, preferably cardboard and wire can be used, which do not essentially increase the costs of production. The cover sustaining ribs of the support and the extension ribs connected to them at one end are made of cardboard strips, whereby the first mentioned ribs are attached to a ring, immovably secured to the upper end of the handle, while the extension ribs are attached with their other ends to a sleeve, slideable along the handle for operation of the ribs, to expand or contract the whole structure. The four corners of the kerchief used as a cover are folded inwardly to form an octagon, closely resembling the outline of a real umbrella cover. The central portion of the kerchief is frictionally held upon the upper ring of the support by a removable outer ring, while the edges are fastened by removable clips to the free ends of the cover sustaining ribs.

With the aforementioned objects in view and others which will become apparent and be detailed during the course of this description, my invention consists in the parts, elements, features and combinations thereof hereinafter described and claimed.

In the accompanying drawing which illustrates the preferred form of this invention and in which similar reference numerals refer to similar features in the different views:

Fig. 1 is a sectional vertical elevation through a partly expanded toy umbrella, involving this invention.

Fig. 2 is an interior view of the toy umbrella in expanded position.

Referring to the drawing, which illustrates a preferred form of this invention, 1 designates a handle, made of one or more kerchiefs wound around a central rod 2, preferably a piece of wire. The lower end of the rod 2 with the kerchief wrapped around is bent to a crook 3. A ribbon 4, wrapped and tied around the handle near the crook 3, prevents unwinding of the respective portion of the kerchief and forms a decoration.

The expandible and contractible umbrella frame consists of a number of cardboard strips 5 and 6, radially extending from the handle 1, of these the strips 5 represent the cover sustaining ribs and the strips 6 the extension ribs. In the preferred embodiment illustrated in the drawing eight ribs are used, but any other number of ribs may be used, without departing from the principle of

2

this invention. The extension ribs 6 are flexibly connected at the upper end to the cover sustaining ribs 5, while the lower ends of the extension ribs 6 are flexibly attached to an encircling sleeve 7, preferably made of cardboard, which is slidably mounted on the handle. In the preferred form of this invention, the extension ribs are glued over approximately half of their length to the cover sustaining ribs as reinforcements. The cover sustaining ribs 5 are at their upper ends flexibly attached to a common ring 8, preferably of cardboard, which is immovably located on the upper end of the handle 1. The ring 8 may be secured to the handle by a pin 9 extending almost diametrically through the layers of the wound kerchief 1 of the handle. The flexibility of the strip material provides for the necessary articulation at the joints, when expanding or contracting the frame by sliding the sleeve 7 along the handle.

A kerchief 10 forms the cover of the umbrella, it has its four corners 10a, 10b, 10c and 10d folded inwardly so as to convert its square shape to an octagonal shape, which closely resembles the outline of a real umbrella cover. The central portion of the kerchief 10 covers the ring 8 and is frictionally held upon the ring by an encircling outer ring 11, preferably of gummed cellulose tape. The edges of the kerchief 10 are attached to the free ends of the cover sustaining ribs 5 with the aid of U-shaped metal clips 12, ordinarily used to attach tags, bent around the ribs and the edges of the cover in such way, that the sides of the U firmly keep the parts in between.

After use as a toy for a sufficient length of time, the umbrella can be easily dismantled, to make proper use of the kerchiefs. It is only necessary, to open the clips 12 and to withdraw the outer ring 11 in order to have the kerchief 10 forming the cover, ready for removal. The ring 8 with the complete frame attached to it, can be slid off the handle 1, as soon as the pin 9 has been pulled off. When the ribbon 4 has been untied, the kerchief 1 can be unwound and also removed.

The preferred embodiment of the invention described above discloses the use of each one kerchief only for the cover and for the handle of the umbrella, however two or more kerchiefs can be used for these elements of the umbrella if deemed feasible.

The invention is not limited to the embodiment described above, many changes can be made and various details of construction may be varied without departing from the principles of this invention.

I claim as my invention:

1. A toy umbrella consisting of a handle comprising at least one wound kerchief, a support provided at one end of said handle for expanding and contracting movements, means slideable upon said handle operatively connected with said support, and a cover comprising at least one kerchief removably attached to said support.

2. A toy umbrella as claimed in claim 1, in which the handle comprises a rod around which the first mentioned kerchief is wound.

3. A toy umbrella as claimed in claim 1, in which the handle comprises a wire around which the first mentioned kerchief is wound, one end of the wire being bent to a crook.

4. A toy umbrella as claimed in claim 1 in which the kerchief forming the cover is of square shape with the four corners thereof folded inwardly whereby the square shape of the kerchief is converted to octagonal shape.

5. A toy umbrella consisting of a handle comprising at least one wound kerchief, a frame of cardboard strips disposed at one end of said handle for expanding and contracting movements, means slideable upon said handle operatively connected with said frame, and a cover com-

prising at least one kerchief removably attached to said frame.

6. A toy umbrella consisting of a handle comprising at least one wound kerchief, a ring secured to the upper end of said handle, cover sustaining cardboard strips attached at one end to said ring, means slidable upon said handle operatively connected with said cover sustaining cardboard strips, and a cover comprising at least one kerchief, removably attached to said ring and said cover sustaining cardboard strips.

7. A toy umbrella consisting of a handle comprising at least one wound kerchief, a ring secured to the upper end of said handle, a sleeve slidable on said handle, cover sustaining cardboard strips connected at one end to said ring, extension cardboard strips connected at one end to said cover sustaining cardboard strips and at the other end to said sleeve, and a cover comprising at least one kerchief removably attached to said ring and to said cover sustaining cardboard strips.

8. A toy umbrella as claimed in claim 7 in which the extension cardboard strips are connected on part of their length to said cover sustaining cardboard strips.

9. A toy umbrella as claimed in claim 6, in combination with an outer ring on the upper end of said handle,

enclosing the central portion of said cover, said outer ring being immovably secured to said handle, and clips adapted to secure the edges of said cover to said cover sustaining cardboard strips.

- 5 10. A toy umbrella consisting of a handle comprising at least one wound kerchief, a ring secured to the upper end of said handle, eight radially extending cover sustaining cardboard strips attached to said ring for expanding and contracting movements, means slidable upon said 10 handle operatively connected with said cover sustaining cardboard strips, and a cover comprising at least one square shaped kerchief having four corners inwardly folded so as to convert the square shape of said last named kerchief to an octagonal shape, removably attached 15 at the central portion to said ring and at its edges to said cover sustaining cardboard strips.
